UNITED STATES PATENT OFFICE.

EDGE T. COPE, OF SALEM, OHIO, ASSIGNOR TO THE BUCKEYE ENGINE COMPANY, OF SALEM, OHIO, A CORPORATION OF OHIO.

BLUE-PRINTING MACHINE.

1,134,589.

Specification of Letters Patent.

Patented Apr. 6, 1915.

Application filed May 29, 1914. Serial No. 841,799.

To all whom it may concern:

Be it known that I, EDGE T. COPE, a citizen of the United States, residing at Salem, in the county of Columbiana and State of Ohio, have invented a new and useful Improvement in Blue-Printing Machines, of which the following is a full, clear, and exact description, reference being had to the accompanying drawings, forming part of this specification, in which—

Figure 1 is a side elevation of a blue printing machine embodying my invention; Fig. 2 is a top plan view of the feeding mechanism for the lamp; Fig. 3 is a vertical section of the same; Fig. 4 is a sectional elevation on the line IV—IV of Fig. 3, of the lamp feeding mechanism; Fig. 4^a is an end elevation of the same; and Figs. 5 and 6 are detail views taken at substantially right angles to each other and showing the lamp carriage.

My invention has relation to blue printing machines of that class which employ transparent cylinders provided with curtains which are moved around the cylinder to hold the drawings and sensitized paper in place.

The present invention is an improvement upon the machine described and claimed in my Patent No. 784,473 of March 7, 1905. The present improvements relate more particularly to the carrying and feeding mechanism for the electric lamp.

In the drawings, the numeral 2 designates the transparent glass cylinder; 3 and 4 the upper and lower rings of the supporting frame for said cylinder, which are spaced apart by the posts 5 and 6.

7 designates supporting legs for the frame, and 8 are movable rollers to which the curtains 16 are attached.

11 and 12 are the wire cables connected to the end portions of the rollers and having counterweights 13 at their lower ends.

45 The parts as thus far described are substantially the same as the corresponding parts of the machine shown in my prior patent above referred to and reference may be had to said patent for more complete description thereof. With the weight and rope connections and the friction on the cylinder, the rollers may be moved around the cylinder and will remain in adjusted position to cover the tracings or drawings and sensitized paper and hold them against the

cylinder. Each curtain is of sufficient length to cover about one-half of the complete cylinder, and the weights hold the curtains and rollers in contact with the cylinder with an even pressure, all as in my said patent.

60 The numeral 14 designates the electric lamp which is arranged to be lowered and raised into and out of the cylinder. This lamp is suspended at 15 from a curved arm 16, which is attached at its lower end to a 65 vertically movable carriage, mounted for travel on the vertical rail 17. This rail 17 is attached to the frame rings 3 and 4 and is shown as being of T-shape in cross section. The whole construction of the carriage is 70 illustrated in Figs. 5 and 6. It comprises the upper and lower brackets or castings 18 and 19, carrying rollers 20 and 21 which embrace and travel on the flanges of the rail 17.

75 22 is a sleeve which is arranged to slide freely on the lower portion of the lamp-supporting arm 16, with the spring 23 seated between its upper end and the under side of the bracket 18.

80 24 is a pulley journaled on the sleeve 22. A cord or cable 25 is connected to the frame of the carriage at one end at 26, and thence extends downwardly underneath this pulley, and thence up and over a pulley 25^a at the 85 upper portion of the bracket. The cord or cable then extends downwardly over suitable pulley 25^b on the top frame ring 3, to the lamp-feeding mechanism hereinafter described. Pivoted to the sleeve 22 are links 27, which at their lower ends are 90 connected to the toothed dogs 28. These dogs are pivoted at 29 to the lower bracket 19 of the carriage and are arranged to grip opposite sides of the rail 17. It will be 95 seen that the spring 23 tends to force the sleeve 22 downwardly and that the devices described form a safety stop to prevent the lamp from falling in case the cord or cable 100 25 should break or become detached.

105 Referring now to Figs. 2, 3, 4 and 4^a, the numeral 30 designates a closed casing within which is journaled a horizontal shaft 31, having an operating crank 32, at its outer end. This shaft carries a drum 33, to which the lower end of the cord or cable 25 is connected. The shaft 31 is formed in two sections, as shown in Fig. 3, the drum 33 being fast to one section and connected to the other section through the medium of a pawl- 110

and-ratchet device 34. Secured to the inner section of the shaft is a gear wheel 35, whose teeth mesh with the teeth of a similar gear wheel 36. These two gear wheels form a rotary pump which is mounted within the sub-casing 37 within the casing 30. This sub-casing has a suitable opening at its lower end communicating with the lower portion of the casing 30, and at its upper portion has a discharge opening 38, which is controlled by the needle valve 39. The needle valve extends upwardly through the top of the casing 30 and carries a turning pointer 40, which may move either to the right or to the left to allow liquid to pass back down into the bottom of the casing 30. The casing 30 is partially filled with oil or other suitable liquid. The weight of the lamp is sufficient to revolve the drum 33 and the pump gears 35 and 36. These gears raise a portion of the liquid up to the opening 38, and the setting of the needle valve determines the amount of liquid which can pass the valve and consequently the speed of descent of the lamp. After the lamp has made this descent, it can be raised by the operation of the crank 32. In this operation, the drum 33 will rotate freely with respect to the inner shaft section, so that the pump gears will not be rotated.

The invention provides a very simple and effective regulator for the lamp. It also provides a safety catch of simple and novel form which will prevent the lamp from falling in case its cord should become broken or detached.

I claim:

1. In a blue printing machine, the combination with a blue printing cylinder, of a lamp adapted to pass within the cylinder, a support for the lamp, a movable carriage carrying the support, and means for controlling the motion of the carriage.
2. In a blue printing machine, the combination with a blue printing cylinder, of a lamp arranged to be lowered into and raised out of said cylinder, a support for the lamp, a carriage to which the support is secured, a vertical rail on which the carriage travels, and means for regulating the motion of the carriage.
3. In a blue printing machine, the combination with a blue printing cylinder, of a lamp arranged to be lowered into and raised

out of said cylinder, a support for the lamp, a carriage to which the support is connected, a vertical rail on which the carriage travels, and a safety catch device on the carriage and arranged to coöperate with the rail.

4. In a blue printing machine, the combination with a blue printing cylinder, of a vertical rail attached to the cylinder, a lamp carriage mounted for vertical travel on said rail, said carriage having a spring-pressed member carrying a pulley, a lamp-feeding cord engaging the pulley, and a safety device connected to said spring-pressed member and arranged to engage said rail upon breakage or disconnection of said cord.

5. In a blue printing machine, the combination with a blue printing cylinder, of a lamp arranged for vertical movement within the cylinder, a vertically movable carriage having a support for the lamp, a cord or cable connected to said carriage, a winding drum for the cord or cable, and a governor for controlling the rotation of said drum in one direction.

6. In a blue printing machine, the combination with a blue printing cylinder, of a lamp-supporting carriage movable vertically within the cylinder, a cord or cable connected to said carriage, a winding drum for the cord or cable, a liquid pump connected to the shaft of the winding drum, and means for regulating the action of the pump to thereby control the unwinding action of the drum.

7. In a blue printing machine, the combination with a blue printing cylinder, of a lamp adapted to move within the cylinder, a support for the lamp secured on a vertically movable carriage, a cord or cable connected to said carriage, a winding drum for the cord or cable, a rotary pump consisting of a pair of toothed wheels mounted on shafts journaled on a casing within which the wheels act together, a valve for regulating the flow of liquid from the pump, and a releasing clutch connecting the pump with the said winding drum.

In testimony whereof, I have hereunto set my hand.

EDGE T. COPE.
